UNITED STATES PATENT OFFICE.

EMIL EBELL, OF NEURUPPIN, GERMANY.

WARP-TENSIONING DEVICE.

1,124,878.

Specification of Letters Patent.

Patented Jan. 12, 1915.

Application filed September 9, 1914. Serial No. 860,824.

To all whom it may concern:

Be it known that I, EMIL EBELL, a German subject, and resident of No. 3, Rheinsbergerstrasse, Neuruppin, German Empire, 5 have invented an Improved and Novel Warp-Tensioning Device, of which the following is a specification.

This invention relates to a warp tensioning device for looms, especially such for the 10 manufacture of so-called strong woven fabrics, particularly driving belts consisting of a plurality of layers which are connected with each other, or interwoven respectively.

The gist of the invention consists in this 15 that each of the various groups of warp threads which all are led in known manner from a spool holding frame to the loom is subjected to the action of a special contrivance that makes it possible to employ 20 threads of different thickness or strength and allows of easily regulating or changing the density of the weft, the tension of the thus acted-on warp threads being, however, always uniform, as will become more clear 25 from the detailed description here following.

In this connection I refer to the accompanying drawing which shows a diagrammatical representation of one form of construction of the device in question shown as 30 an example; this form of execution is intended especially for looms for belts, the warp threads of which are to be led to the loom in groups located one above the other; 35 there are three such groups in the example in question.

The loom proper is merely indicated by the letter A. a a^1 a^2 are the three sets or groups of warp threads which are coming 40 from spools, *i. e.* sets or groups of such spools, not shown. b b^1 b^2 are thread guides. Since there are in the example shown three groups of threads and consequently, three thread guides, there are also three of the 45 special tensioning devices before-mentioned which are of like construction. Owing to this latter fact, it is sufficient to describe only one of them.

c d e f are four rollers, of which d e f 50 are connected with each other by cog wheels, as shown; the shafts or pivots of these rollers with their gearing-forming pinions are supported in the frame of the apparatus.

The fourth or, more precisely, first roller, 55 *viz.* c , is carried by two levers g fulcrumed also to the frame and having each a weight

g^1 which may be displaced upon the respective lever so as thereby to regulate or change the pressure exerted by the weight upon the roller c and thus upon the roller d , too, 60 the roller c being in immediate contact with said other roller. The intermediate roller e is supported in the frame not directly but indirectly by the mediation of vertically adjustable bolts, as shown in dotted lines, 65 so that the roller e may be adjusted in height with respect to the rollers d and f , or, in other words, may be adjusted with respect to the thickness of the threads to be passed through between the rollers in question. 70

The threads are led from the guide b (or b^1 or b^2 respectively) over the roller c , through between the rollers c and d , through between the rollers d and e , and through between the rollers e and f , as shown. Between c and d they are subjected to the combined pressure of the parts c g g^1 , and between the rollers e and d , as well as e and f , they pass through with either no additional friction at all or but little one, the distance 80 between these rollers being generally determined exactly according to the thickness of the respective threads. There is, however, another means provided by which the threads may be, and are, put under tension, 85 *viz.* a band brake h^1 coöperating with a disk or pulley h keyed to the shaft of the roller d . The band h^1 is connected at one end with the frame of the apparatus and at the other end with a lever i bearing a weight i^1 . 90 Obviously the band h^1 is exposed to the pull of the weighted lever i i^1 and the resistance thereby produced is transmitted by the disk or pulley h and the roller d to the threads which are thus subjected to a tension of corresponding degree. 95

It becomes obvious from the above description that comparatively thin, as well as comparatively thick threads may be led to the loom under uniform tension, and as this latter may be changed by the means described, whereas the shuttle reciprocates without any change whatever in respect to speed, the density of the fabric may be changed or regulated corresponding to the 100 requirements of the case.

Having now described my invention, what I desire to secure by a patent of the United States is:

In a warp tensioning device, the combination, with a plurality of groups of warp threads, of a like number of sets of rollers 110

comprising each four rollers; adjustable weighted levers so arranged as to be adapted to press the first roller against the second; a gearing connecting the second, third, and 5 fourth roller with each other; means for adjusting the third roller with respect to the second and the fourth; and an adjustable brake so arranged as to be adapted to coöperate with the second roller and tending 10 to counter-act its rotation by frictional

resistance, substantially and for the purpose as described.

In witness whereof I have hereunto signed my name this 15 day of August 1914, in the presence of two witnesses.

EMIL EBELL.
